US00D910142S

(12) **United States Design Patent** (10) Patent No.: **US D910,142 S**
 Weider Samuelsen et al. (45) Date of Patent: ** Feb. 9, 2021

(54) **SLUDGE SEPARATOR WITH A SINGLE WATER/OIL MEMBRANE SEPARATOR LOOP**

(71) Applicant: **Rena Quality Group AS**, Stavanger (NO)

(72) Inventors: **Ørjan Weider Samuelsen**, Hafsfjord (NO); **Bent Atle Randa**, Raege (NO)

(**) Term: **15 Years**

(21) Appl. No.: **35/507,820**

(22) Filed: **May 6, 2019**

(80) **Hague Agreement Data**

Int. Filing Date: **May 6, 2019**

Int. Reg. No.: **DM/204021**

Int. Reg. Date: **May 6, 2019**

Int. Reg. Pub. Date: **Nov. 22, 2019**

(30) **Foreign Application Priority Data**

Nov. 20, 2018 (NO) 20181013

(51) **LOC (13) Cl.** **23-01**

(52) **U.S. Cl.**

USPC **D23/207**

CPC **C02F 9/00** (2013.01)

(58) **Field of Classification Search**

USPC D23/207-209; 210/232-234, 223, 282

CPC C02F 9/00; C02F 1/003; B01D 19/0031;

B01D 35/30; B01D 35/12; B01D 35/14

Primary Examiner — Richard E Chilcot

CLAIM

The ornamental design for a sludge separator with a single water/oil membrane separator loop, as shown and described.

DESCRIPTION

- 1.1 is a front, right perspective view
- 1.2 is a rear, right perspective view thereof
- 1.3 is a front view thereof
- 1.4 is a rear view thereof
- 1.5 is a right side view thereof
- 1.6 is a left side view thereof
- 1.7 is a top view thereof
- 1.8 is a bottom view thereof

1 Claim, 8 Drawing Sheets
